(57) **CLAIM**

The ornamental design for an enclosure for RF testing within an environmental chamber, as shown and described.

DESCRIPTION

FIG. 1 is a front perspective view of an enclosure for RF testing within an environmental chamber, shown with the door open.

FIG. 2 is a front view of the enclosure of FIG. 1, shown with the door closed.

FIG. 3 is a rear view of the enclosure of FIG. 1, shown with the door closed.

FIG. 4 is a right side view of the enclosure of FIG. 1, shown with the door closed.

FIG. 5 is a left side view of the enclosure of FIG. 1, shown with the door closed.

FIG. 6 is a top view of the enclosure of FIG. 1, shown with the door closed; and,

FIG. 7 is a bottom view of the enclosure of FIG. 1, shown with the door closed.

The broken lines form no part of the claimed design.
